UNITED STATES PATENT OFFICE.

FRANKLIN KING CHASE, OF TAUNTON, MASSACHUSETTS.

STOVE-SHELF.

SPECIFICATION forming part of Letters Patent No. 655,194, dated August 7, 1900.

Application filed December 18, 1899. Serial No. 740,743. (No model.)

To all whom it may concern:

Be it known that I, FRANKLIN KING CHASE, a citizen of the United States of America, residing at Taunton, in the county of Bristol 5 and State of Massachusetts, have invented certain new and useful Improvements in Stove-Shelves, of which the following is a specification.

This invention relates to cooking-stoves, 10 and has for its object to provide an improved means for securing the pipe thereto, whereby the products of combustion will be directly communicated to the chimney-flue from the stove, and whereby the stove can be secured 15 flush against the wall, thus requiring a minimum amount of space.

With these objects in view my invention consists in certain novel parts and combinations of parts, all of which will be specifically 20 described hereinafter, recited in the claims, and illustrated in the accompanying drawings, in which—

Figure 1 is a perspective view of a stove or range embodying my invention. Fig. 2 is a 25 vertical longitudinal section on the line 2 2 of Fig. 3. Fig. 3 is a longitudinal transverse section on the line 3 3 of Fig. 2. Fig. 4 is a similar view on the line 4 4 of Fig. 2, and Fig 5 is a top plan view of the warming-shelves. Fig. 30 6 is a detail view of the removable plate.

Referring now to the drawings by reference-numerals, 1 designates a stove or range which may be of any ordinary construction, to the top of which is arranged a panel 2 along the 35 edge of the side containing the smoke-outlet 3. This smoke-outlet will preferably be arranged centrally of the stove, to one side of the longitudinal center, and will be surrounded by the projecting pipe-collar 4. On the top 40 of the panel 2 is secured by any suitable means a shelf 5, provided with an opening 6 of about the same size as the pipe-protecting casing 7, the respective ends of which lie tightly against the stove-top and the under

45 side of the shelf. A second panel 8 rests upon the first-named panel and is removably secured thereto by means of the side brackets 9 and 10, which support on their top edges the second shelf 11, projecting from the top edge 50 of the panel 8. To add rigidity to the panel 8 and the entire structure, the forwardly-pro-

jecting flanges 12 and 13 are cast or otherwise secured on the respective ends thereof which coincide with and are secured to the brackets 9 and 10, respectively, by suitable bolts 14. 55 The top shelf is also provided with an opening of about the same size and which alines with the opening 6 in the shelf 5.

15 is a removable substantially $\sqcap$ -shaped plate secured in a registering opening in the 60 panel 8 by suitable screws or bolts 16.

To add a finish to the structure heretofore described and provide a back for the shelf 11, a third panel or shelf-back 18 is arranged and provided with a suitable fanciful design, such 65 as may suggest itself to the manufacturers of this invention.

Having thus described the construction of the invention, I will now proceed to describe its application and the means of operation. 70

After assembling all the parts suppose it is found that the pipe-opening in the chimney is on a line with the top of the stove. The pipe can be connected directly with the collar 4 by an elbow, when the stove can be 75 forced directly against the wall. Should the chimney-opening be opposite the middle panel, the plate 15 can be removed and a line of pipe run up through the pipe-casing until it is opposite the opening after passing 80 through the opening in the first shelf and connected to the chimney by an elbow. If the flue-opening is about on a line with the top of the second shelf, the middle panel can be reversed, causing the $\sqcap$ -shaped opening 85 to be reversed (thus $\sqcup$) and the pipe can be manipulated, or if the hole is above the top panel the pipe can be run up above the entire structure through the alining openings in the respective shelves and connected to the 90 chimney by an elbow, as before described. Thus it will be seen that I provide for securing the pipe-line directly to the chimney without unnecessary delay and with a minimum amount of labor. 95

What I claim as my invention is—

1. The combination with a stove and the pipe-opening thereof; of a shelf secured to said stove and carrying a casing open at top and bottom, a panel above said casing provided with an opening at right angles to the top opening of the casing, and a removable 100

- plate normally covering the opening in the panel, substantially as described.
2. The combination with a plurality of shelves designed to be secured to a stove; of an open-ended casing carried by said shelves and registering with the pipe-opening in said stove, the top of said casing terminating at its juncture with the first shelf, a flat panel above, and on a line with the rear of the casing, and provided with an opening through which the stove-pipe can project, and a removable plate for normally keeping the last-named opening closed, substantially as described.
15. 3. The combination with a plurality of shelves adapted to be secured to a stove and a casing carried by the shelves and registering with the pipe-collar of the stove; of a removable and reversible panel connecting two of the shelves and having an opening through which the pipe can project the position of which is adapted to be changed by the reversal of said panel, substantially as described.
4. The combination with a stove and its pipe-opening; of a panel arranged thereon; a casing carried by said panel and registering with the collar, a shelf projecting from said panel and provided with an opening registering with an opening in the top of the casing and a removable plate secured to the rear of
- the panel and casing, substantially as described.
5. The combination with a stove and its pipe-collar; of a panel arranged on one side of the stove, a casing carried by said panel and covering said collar, a shelf projecting from said panel and having an opening in alinement with an opening in the top of the casing, a second panel secured to the first panel, having an opening, and a removable plate normally covering the last-named opening, substantially as described.
6. The combination with a stove and its flue-opening, of a casing surrounding said opening, a panel secured to the stove and casing, a shelf projecting from the panel and having an opening in line with the first-named openings, a reversible panel secured to the first-mentioned panel and provided with an opening at right angles to the opening in the shelf and a second shelf projecting from the last-named panel also having an opening therein, substantially as described.

In testimony whereof I affix my signature in presence of two witnesses.

FRANKLIN KING CHASE.
